UNITED STATES PATENT OFFICE.

HERBERT W. CHRISTIAN, OF DETROIT, MICHIGAN.

COMBINED WATER HEATER AND DRIPPER.

1,302,309.

Specification of Letters Patent. Patented Apr. 29, 1919.

Application filed August 19, 1918. Serial No. 250,594.

To all whom it may concern:

Be it known that I, HERBERT W. CHRISTIAN, a citizen of the United States of America, residing at Detroit, in the county 5 of Wayne and State of Michigan, have invented certain new and useful Improvements in Combined Water Heaters and Drippers, of which the following is a specification, reference being had therein to the 10 accompanying drawings.

My invention aims to provide a combined water heater and dripper that may be advantageously used in hospitals for various treatments or purposes, the device including 15 a main reservoir in which water or solutions may be placed and automatically fed into an auxiliary reservoir in which is located heating elements, a thermometer, and a thermostat, the heating elements being electrically operated and automatically controlled 20 by the thermostat.

My invention further aims to provide a simple, durable and easily regulated device of the above character that may be operated 25 from an ordinary electric lighting system, either of one hundred and ten or two hundred and twenty volts, the device being provided with a switch that not only serves its usual purpose, but permits of the heating 30 element being manually regulated to perform predetermined work.

The device will be hereinafter described and then claimed and reference will now be had to the drawing, wherein—

35 Figure 1 is a front elevation of the combined water heater and dripper;

Fig. 2 is a vertical sectional view of the same;

40 Fig. 3 is a horizontal sectional view taken on the line III—III of Fig. 2;

Fig. 4 is a similar view taken on the line IV—IV of Fig. 2;

Fig. 5 is a similar view taken on the line V—V of Fig. 2;

45 Fig. 6 is an enlarged vertical sectional view of a thermostat adapted to form part of the device;

Fig. 7 is a horizontal sectional view of the thermostat, taken on the line VII—VII of 50 Fig. 6, and

Fig. 8 is a diagrammatic view illustrating the electrical connections of the device.

In the drawings, the reference numeral 1 denotes a cylindrical or tubular metallic 55 body 1 provided with spaced partitions 2 and 3, said partitions being set in from the

ends of the body and soldered or otherwise secured thereto so as to be practically integral with said body. The ends of the body are interiorly screwthreaded, as at 4, and 60 said body is provided with apertured ears 5 and a bracket 6, the former permitting of the body being suspended from a suitable support, and the latter permitting of said body being rigidly secured to a support. 65

7 denotes a main reservoir, preferably in the form of a glass tube having its ends exteriorly screwthreaded, so that one end of the main reservoir may be screwed into the upper end of the body 1 and the opposite 70 end of said reservoir provided with a detachable cap 8. Gaskets 9 are used at both ends of the main reservoir 7 and after said reservoir is screwed into the upper end of the body 1, cement or other material may 75 be employed for fixing the main reservoir relative to the body 1 to avoid any leakage between the lower end of the main reservoir and the upper end of the body 1. By removing the cap 8, the main reservoir may 80 be easily filled.

10 denotes an auxiliary reservoir having its ends exteriorly screwthreaded and one end thereof mounted in the lower end of the body 1 and the opposite end thereof provided with a closure cap 11. Cement or other material is also used to fix the ends of the auxiliary reservoir 10 so as to avoid leakage and gaskets 12 will contribute to this result. 90

13 denotes a pipe axially of the tubular body 1 establishing communication between the reservoirs 7 and 10, said pipe being suitably held by the partitions 2 and 3 with the lower end of the pipe extending into the 95 auxiliary reservoir and reduced to form a nipple 14, which may be closed by a valve 15 on a float or buoyant body 16 located within the auxiliary reservoir 10. The valve 15 and its supporting float constitute automatic means for preventing the auxiliary reservoir 10 from being flooded by the contents of the main reservoir 7. 100

17 denotes a valve carried by the pipe 13, said valve being preferably of the needle 105 type so that the same may be minutely regulated by a valve stem 18 extending out of the body 1. By adjusting the valve stem 18 the contents of the main reservoir 7 may enter the auxiliary reservoir 10, drop by 110 drop, and thus provide an intermediate feed between the main and auxiliary reservoirs,

19 denotes a partition within the lower end of the auxiliary reservoir 10 and in spaced relation to the bottom gasket or washer 12, said partition having a series of 5 openings to cooperate with the partition 3 in the body 1 in supporting a thermometer 20, electric heating elements 21, and a thermostat 22; the float or buoyant body 16 being recessed or cut away to provide clearance for the elements 20 to 22 inclusive which are disposed longitudinally of the auxiliary reservoir 10.

10 The thermometer 20 is of a conventional form as used in hospitals for determining 15 the temperature of water, and said thermometer may be safely held relative to the partitions 3 and 19 by rubber gaskets 23.

The thermostat 22 is preferably in the 20 form of a metallic tube having the upper end thereof open and both ends held relative to the partitions 3 and 19 by peripheral flanges 4. In the lower end of the tube 22 is located an insulator 25 and connected to said insulator by screws 26 or other fastening means are arms 27 and 28, the former being made of materials susceptible to expansion and contraction by the temperature of the water in the auxiliary reservoir 10, and the latter is resilient in order that it 25 may be adjusted by a set screw 29 adjustable at the upper end of the tube 22 and extending through the tubular body 1. The ends of the arms 27 and 28 are in proximity to each other and are adapted to normally 30 contact, said arms being in an electric circuit as will hereinafter appear. The arms protrude out of the upper end of the tube 22 and may be observed through an opening 30 in the tubular body 1 of the device.

40 The electric heating elements 21 are two in number, each comprising a suitable casing having coils 31, 32 therein suitably insulated from each other, as at 33. The coils of one heating element are adapted for currents 45 of one hundred and ten volts and the coils of the other heating element for a current of two hundred and twenty volts, but it is possible to dispose the coils so that both heating elements may be placed in a circuit 50 of one hundred and ten volts or a circuit of two hundred and twenty volts. To accomplish this, a novel switch 34 is employed, said switch being in the form of an oblong cylindrical casing containing contacts 40 55 to 43 inclusive adapted to be engaged by a contact member 44 slideable on a rod 45 and operable from the exterior of the switch casing. Cables may extend into and through the switch casing to carry the necessary wires or conductors for the heating elements 21, the thermostat 22, and an electric light socket 46 which permits of the combined device being connected to and operated from an ordinary electric lighting circuit.

By reference to Fig. 8, it will be noted that the coil 31 and the thermostat 22 are adapted to be connected by wires 47 to a suitable source of electrical energy, and then the thermostat 22 is connected by a wire 70 75 to the rod 45, while the coil 31 is connected by a wire 49 to the contact 40. With the thermostat 22 normally closed, there is an electric circuit through the coil 31 for an initial heat in the auxiliary reservoir. By shifting the contact member 44 to bridge the contacts 40 and 41, the coil 32 is brought into circuit through the medium of the wires 50 and 51. This may be for a current of one hundred and ten volts and should it be 80 desired to operate the other electric heating element in connection with a current of two hundred and twenty volts the contact member 44 is shifted to the contact 42 or to bridge said contact with the contact 43, 85 when similar circuits will be established as in connection with the heating element previously mentioned.

From the foregoing, it will be observed 90 that either or both of the heating elements may be utilized, according to the electrical connections, for heating the water or liquid admitted to the auxiliary reservoir 10 from the main reservoir 7, and by regulating the thermostat 2, it is possible to have the contents of the auxiliary reservoir 10 heated to a predetermined temperature and then the electric current automatically cut off until the temperature of the contents of the reservoir is lowered to a predetermined point, when an electric circuit will again be automatically established to heat the water or solution within the auxiliary reservoir.

Any suitable provision may be made, as 105 at 52, for removing the contents of the auxiliary reservoir 10. A conventional form of pet cock has been shown so as to permit of the contents of the reservoir being removed drop by drop or in a very small 110 stream.

It is thought that the operation and utility of the device will be apparent without further description, and while in the drawing there is illustrated a preferred embodiment of my invention, it is to be understood that the structural elements are susceptible to such variations and modifications as fall within the scope of the appended claims.

What I claim is:—

1. A combined water heater and dripper comprising a body, a main reservoir connected to the upper end thereof, an auxiliary reservoir, connected to the lower end of said body, means in said body establishing communication between said main reservoir and said auxiliary reservoir, electric heating elements in said auxiliary reservoir, and means in said body adapted to regulate the operation of said electrical elements.

120

125

130

2. A combined water heater and dripper comprising a body, communicating reservoirs connected thereto, heating means in one of said reservoirs for the contents thereof, and means in said body adapted to regulate said heating means. 5 and means adapted for manually adjusting said thermostat.
3. A device of the type described comprising a body, reservoirs connected thereto, means in said body establishing communication between said reservoirs and adapted to regulate the passage of the contents of one reservoir into the other, and means in one of said reservoirs adapted for heating the contents thereof. 10
4. A device of the type described comprising a body, reservoirs connected thereto, means in said body establishing communication between said reservoirs, electric heating elements in one of said reservoirs, a thermostat in the same reservoir in circuit with said electric heating elements, and means exteriorly of said device adapted for controlling the operation of either of said electric heating elements. 15
5. A device of the type described comprising superposed reservoirs, means between said reservoirs establishing communication therebetween and adapted to regulate the passage of the contents of one reservoir into the other, heating elements in the lowermost reservoir, a thermostat in the same reservoir, 20
6. A device of the type described comprising a hollow body, reservoirs connected to the ends of said body, a connection in said body establishing communication between said reservoirs, means carried by said connection adapted for regulating the communication between said reservoirs, an electric heating element in one of said reservoirs, a thermostat in the same reservoir in circuit with said electric heating element, and means carried by said body adapted for adjusting said thermostat. 25
7. A device of the type described comprising a body, transparent reservoirs carried thereby, a connection in said body establishing communication between said reservoirs, a valve carried by said connection, a float actuated valve in one of said reservoirs controlling communication between said reservoirs in addition to the valve of said connection, and means in the same reservoir adapted for heating the contents thereof. 30

In testimony whereof I affix my signature in the presence of two witnesses.
